UNITED STATES PATENT OFFICE.

ADOLPH G. SCHULTZ, OF HINCKLEY, ILLINOIS.

GEARING FOR WASHING-MACHINES.

SPECIFICATION forming part of Letters Patent No. 665,348, dated January 1, 1901.

(Application filed April 16, 1900. Serial No. 12,980. No model.)

To all whom it may concern:

Be it known that I, ADOLPH G. SCHULTZ, a citizen of the United States, residing at Hinckley, in the county of De Kalb and State 5 of Illinois, have invented certain new and useful Improvements in Gearing for Washing-Machines, of which the following is a specification.

This invention relates to improvements in 10 that class of washing-machines in which a rotary agitator or stirring device located in a tub or receptacle is employed for cleansing the garments; and it consists in certain peculiarities of the construction, novel arrangement, and operation of the various parts thereof, as will be hereinafter more fully set forth and specifically claimed.

The principal object of my invention is to 15 provide a simple, inexpensive, and efficient mechanism by means of which the agitator or stirring device may be rotated first in one direction and then in the opposite direction by conversion of motion from a shaft having a continuous rotary motion in one direction.

20 In order to enable others skilled in the art to which my invention pertains to make and use the same, I will now proceed to describe it, referring to the accompanying drawings, in which—

25 Figure 1 is a view in elevation of my improved mechanism for washing-machines, showing it in position on a portion of a tub or receptacle for the clothes and water. Fig. 2 is a plan sectional view taken on line 2 2 of 30 Fig. 1; and Fig. 3 is a detail view of a portion of the supporting-frame for the driving mechanism, showing an inclined piece secured thereto for the purpose of changing the motion of the agitator.

35 Similar letters refer to like parts throughout the different views of the drawings.

A represents a portion of a tub or other receptacle to be used for holding the clothes and water in which they are washed. This 40 receptacle may be of any suitable size, form, and material, but preferably has its upper end open and formed with an annular recess a in its rim to receive and retain a cover B of suitable size to close the top of the tub or 45 vessel.

50 Mounted on the cover or support B is a

frame C, which is preferably rectangular, as shown in Fig. 1 of the drawings.

Horizontally journaled in suitable bearings d and d' is a driving-shaft D, which has on 55 its outer end a crank-handle D' to be used for operating the machine and on its inner end a beveled gear F, which meshes with the beveled gears G and G', both of which are loosely mounted on a vertical shaft H, which 60 is journaled in the frame C and in the support or cover B, which rests on the top of the vessel or tub or may be located thereabove. Each of the gears G and G' is provided with a segmental slot or depression g near its periphery for the reception of the shifting bar or rod H', as will be presently explained.

Rigidly secured to the vertical shaft H, between the hubs of the gears G and G', is a yoke I, the prongs i of which are provided 70 with openings i' for the reception and operation of the shifting bar H', which is preferably angular in cross-section, as shown in Fig. 2 of the drawings.

Secured to the yoke I and extending about 75 midway between the prongs i is a spring K, the outer end of which rests against the bar H' and prevents its accidental engagement with the lower gear.

Journalized on the outer surface of the bar 80 H' at about its middle is a roller h, which impinges the inclined piece L, which is secured to the side of the frame C opposite that side thereof in which the driving-shaft is journaled. The vertical shaft H extends some 85 distance into the tub or receptacle and has its lower portion formed or provided with a laterally-extending enlargement h', which fits in a correspondingly-shaped opening in the agitator M, which is provided with a number 90 of arms m and is preferably of the form shown in Fig. 1 of the drawings. This agitator is vertically movable on the enlargement h' of the vertical shaft H, but will rotate therewith by reason of the shape of the said enlargement 95 and the opening in the agitator in which it is located.

In the drawings I have shown the driving-shaft as being journaled on the frame C, and while I prefer to so construct the device yet 100 I may provide other bearings therefor, and instead of mounting the mechanism on the

cover B, I may mount it on a suitable support, which can be placed on the top of the vessel or above the same, so that the agitator will be located in the vessel or receptacle without departing from the spirit of my invention.

The operation is as follows: By turning the driving-shaft in the direction indicated by the arrow thereon it is apparent that the gear G will be driven in one direction and the gear G' in the opposite direction, and as the yoke I, which carries the bar H', is fixed to the vertical shaft H said shaft and the agitator M will be rotated in one direction until the roller h on the shifting bar H' impinges the inclined piece L, which will force the bar up or down, thus causing it to alternately engage the gears G and G', and thereby reverse or alternate the movement of the agitator, which operation will thoroughly stir and churn the garments, so as to remove all dirt and stains.

Having thus fully described my invention, what I claim as new, and desire to secure by Letters Patent, is—

In a gearing for a washing-machine the

combination with a vertical shaft journaled 25 on a suitable support, of a driving-shaft horizontally journaled with one of its ends near the vertical shaft, a beveled gear on the inner end of the driving-shaft, a beveled gear having a segmental slot or depression near its periphery and loosely mounted on the vertical shaft so as to engage the upper portion of the gear on the driving-shaft, another beveled gear having a segmental slot or depression 30 near its periphery and loosely mounted on the vertical shaft so as to engage the lower portion of the gear on the driving-shaft, a yoke fixed to the vertical shaft, a vertically-movable bar movably secured in the prongs of the yoke, and having a roller on its outer 35 surface, a spring to press said bar, an inclined piece located near the vertical shaft and in the path of said roller, substantially as described.

ADOLPH G. SCHULTZ.
